(57) **CLAIM**

The ornamental design for a therapeutic cushion, as shown and described.

DESCRIPTION

FIG. 1 is a top perspective view of a therapeutic cushion showing my new design;

FIG. 2 is a bottom perspective view thereof;

FIG. 3 is a right elevational view thereof, where the left elevational view is identical thereto;

FIG. 4 is a top plan view thereof;

FIG. 5 is a front elevational view, where the rear elevation view is mirrored thereto;

FIG. 6 is a bottom plan view thereof; and,

FIG. 7 is a supplemental view of the therapeutic cushion installed along a therapeutic pad assembly.

The broken lines in FIGS. 1-6 depict portions of the article that form no part of the claimed design. The broken lines in FIG. 7 depict environment which forms no part of the claimed design.

1 Claim, 7 Drawing Sheets
